United States Patent Office

Des. 212,649
Patented Nov. 5, 1968

212,649

CONTACT LENS CASE

Charles H. Kolbeck, 10570 W. Grantosa Drive,
Wauwatosa, Wis. 53222

Filed June 28, 1967, Ser. No. 7,627

Term of patent 14 years

(Cl. D57—1)

FIG. 1

FIG. 2

FIG. 3

FIG. 4

FIG. 5

FIG. 1 is a top plan view of a contact lens case, showing my new design.

FIG. 2 is a front elevational view of FIG. 1.

FIG. 3 is a top perspective view of FIG. 1.

FIG. 4 is a side elevational view of FIG. 1.

FIG. 5 is a bottom plan view of FIG. 1.

I claim:

The ornamental design for a contact lens case, substantially as shown.
